[57] **CLAIM**

The ornamental design for a motor vehicle window protector assembly, as shown and described.

DESCRIPTION

FIG. 1 is a front perspective view of a window protector assembly showing our new design as viewed from the outside of a motor vehicle;

FIG. 2 is a bottom plan view thereof;

FIG. 3 is a front elevational view thereof;

FIG. 4 is a top plan view thereof;

FIG. 5 is a left side elevational view thereof, when viewed from the outside of a motor vehicle;

FIG. 6 is a rear elevational view thereof as viewed from the inside of a motor vehicle;

FIG. 7 is a right side elevational view thereof when viewed from the outside of a motor vehicle;

FIG. 8 is a cross-sectional view taken along lines 8—8 thereof of FIG. 1; and,

FIG. 9 is a cross-sectional view taken along lines 9—9 thereof of FIG. 1.
